UNITED STATES PATENT OFFICE.

EDWARD EBI, OF CEDAR RAPIDS, IOWA.

COUPLING FOR BRAKE-RODS.

SPECIFICATION forming part of Letters Patent No. 276,370, dated April 24, 1883.

Application filed March 9, 1883. (Model.)

To all whom it may concern:

Be it known that I, EDWARD EBI, of Cedar Rapids, Linn county, Iowa, have invented a new and Improved Coupling for Brake-Rods, 5 of which the following is a full, clear, and exact description.

This invention relates to the brake-rods extending the length of the train for operating all the brakes simultaneously, and has for its 10 object to facilitate the coupling of the brake-rods of the several cars of a train.

The invention is an improvement of the 15 brake-rod for which United States Letters Patent No. 265,773 were issued to me on the 10th day of October, 1882; and it consists of guide-blocks loosely mounted on the brake-rods, and provided at the outer ends with beveled prongs, which guide-blocks guide the clutch-disks at 20 the ends of the brake-rods together, so that they can engage. The blocks are provided with devices for locking them together.

The invention also consists in certain parts 25 and details and combinations of the same, as will be fully set forth and described herein-after.

Reference is to be had to the accompanying 30 drawings, forming part of this specification, in which similar letters of reference indicate corresponding parts in all the figures.

Figure 1 is a longitudinal elevation of my 35 improved coupling for brake-rods, showing the manner in which it is applied. Fig. 2 is an end elevation of the same, showing the latches in different positions; and Fig. 3 is a perspective of one of the coupling-blocks, showing the latch removed.

The ends of the brake-rods A, held longitudinally under the cars, are journaled in downward projections A' on the ends of the car, 40 and to the ends of the rods A rods B are hinged, which terminate in clutch-disks C, having teeth on the end circular surfaces.

On the rods B guide-blocks D are loosely 45 mounted to turn in such a manner that the clutch-disks C will be contained within recesses on the said blocks. The blocks D are provided in the free ends with recesses forming two diagonally-opposite beveled tapered prongs, D', 50 on the outer end of each block. The edges of each prong are formed by two diagonal lines extending from two diagonally-opposite corners at the inner end of the block to a point

at the outer end of that edge which is between the two diagonally-opposite edges at which the lines start at the inner end of the block. 55 Both prongs D are made in the same manner. A collar or flat ring, E, is loosely mounted on each rod B between the inner end of a block, D, and a fixed collar, F, mounted on the rod B. A spiral buffer-spring, G, surrounds each 60 rod B between the collar F and the projection A'. The ring or collar E is provided at diametrically-opposite points with a pair of jaws, H, between one pair of which a locking-bar, J, is pivoted. One of the jaws of the other pair is 65 provided with a pivoted spring hook latch, K, adapted to swing in the plane of the collar. The end of the prong of the hook is beveled.

Each block is provided at the inner end of one surface with an eye or ring, L, through 70 which a horizontal rod, M, passes, which projects from the projection A'. The rod M is also suspended by means of a chain, N, from the draw-head O. At its free end each locking-bar is provided with a beveled notch, P. 75

The operation is as follows: When the cars 80 come together, the beveled sides of the projections D' of the blocks D strike against each other until they fit snugly, and thereby guide the clutch-disks C against each other, so that 85 they can engage. The coupling-blocks D are then locked together by swinging the free ends of the locking-bars J in between the corresponding jaws, H, provided with the latches K. By pressing the bars J between the jaws H the latches K will be pressed outward, 90 and will then snap back under the action of the springs, and thus lock the bars J in place. The blocks D thus serve as guides, and greatly facilitate bringing the clutch-disks C together, 95 so that they can engage.

Having thus described my invention, I claim as new and desire to secure by Letters Patent—

1. The combination, with brake-rods, of clutch-disks on the ends of the same, and of 95 guide-blocks provided on the outer ends with beveled prongs, which blocks are loosely mounted on the ends of the said rods, substantially as herein shown and described, and for the purposes set forth.

2. The combination, with brake-rods, of clutch-disks on the ends of the same, guide-blocks loosely mounted on the said rods and provided at the outer ends with beveled prongs,

and of rods for locking the blocks together, substantially as herein shown and described, and for the purpose set forth.

3. The combination, with the brake-rods A, of the rods B, hinged thereto, the clutch-disks C on the ends of the rods B, the spindle-blocks D, loosely mounted on the rods B, and provided with beveled prongs D' at the free ends, and of devices for locking the blocks D together, substantially as herein shown and described, and for the purpose set forth.

4. The combination, with brake-rods, of clutch-disks C, the blocks D, provided with beveled prongs D', the collars E, provided with jaws H, the locking-bars J, pivoted to the jaws, and the spring-latches K, substantially as herein shown and described, and for the purpose set forth.

5. The combination, with brake-rods, of the clutch-disks C, the blocks D, having beveled

prongs D', the eyes or rings L, and the rods M, passing through the said rings or eyes, substantially as herein shown and described, and for the purpose set forth.

6. The combination, with brake-rods, of the clutch-disks C, the blocks D, having beveled prongs D', the eyes or rings L, the rods M, and the chains N, substantially as herein shown and described, and for the purpose set forth.

7. The combination, with brake-rods, of the clutch-disks C, the blocks D, having beveled prongs D', the loose collars E, having jaws H, the locking-bars J, the latches K, and the fixed collars F, substantially as herein shown and described, and for the purpose set forth.

EDWARD EBI.
